UNITED STATES PATENT OFFICE.

JOHN P. BADENHAUSEN, OF PHILADELPHIA, PENNSYLVANIA.

SUPERHEATER.

1,404,565.

Specification of Letters Patent. Patented Jan. 24, 1922.

Application filed May 27, 1916. Serial No. 100,267.

To all whom it may concern:

Be it known that I, JOHN P. BADENHAUSEN, a citizen of the United States, residing at Philadelphia, in the county of Philadelphia and State of Pennsylvania, have invented new and useful Improvements in Superheaters, of which the following is a specification.

This invention relates to the application of superheaters to water-tube boilers, and its principal object is to locate the superheater, or superheaters if more than one be used, in such a way as to bring the superheating surfaces into more intimate contact with the furnace heat than has been previously accomplished.

Another object of the invention is to provide means whereby the steam from the boiler is, before entering the superheater, deprived of all entrained water so that the superheater will be employed for superheating only, instead of for evaporating entrained water as is the case in the various forms of superheaters hitherto in general use.

With the above and other objects in view, the improvement resides in the construction, combination and arrangement of parts set forth in the following specification.

In the drawings—

Figure 1 is a vertical sectional view taken through a water tube boiler and illustrating the application of the superheater employed in the present invention and its location with respect to the various parts of the boiler,

Figure 2 is a similar view illustrating a modified form of boiler and disclosing the connection of the superheater therewith,

Figure 3 is a view similar to Figure 2 illustrating a still further modified form of associating the superheater with the steam drum of the boiler, and

Figure 4 is another modified form of superheater construction.

Similar characters of reference denote corresponding parts throughout all the views of the drawings.

While the drawings disclose water tube boilers having slightly differing details of construction, it should be understood that the novelty in the present invention resides in the location of the superheater therefor and that the same is applicable to other forms of boilers. Said boilers however, have been fully described and set forth in my co-pending patent application, bearing Serial No. 81977, filed March 3rd, 1916, and No. 85124,

filed March 18th, 1916, and the superheater comprising the present invention is preferably used in conjunction with the aforesaid applications. Referring to Figure 1 of the drawings a superheater B is positioned within the walls of a boiler C, the latter in this instance consisting of a plurality of water drums 1, connected by banks of water conducting tubes 2, which comprise a water circulating and a steam generating system of the boiler. The superheater B employed in the present invention is substantially V-shaped in contour and consists of transversely extending headers 3, which are connected by the banks of tubes 4. It should be understood, however, that any other type of superheater, other than a superheater B, may be used as well, regardless of the arrangement of the headers 3 and the connecting tubes 4, or whether the steam flows in series or in parallel through said tubes 4, as this invention is not concerned with the detailed design or type of superheater, but deals more particularly to its location with reference to the parts of the types of boilers shown, and in the manner in which heat is brought into contact with the superheating surface thereof.

The tubes 2 positioned immediately above the grate 5, are provided on their upper side, at a point contiguous to the lower drum 1, with a gas directing baffle wall 6, extending parallel to the tubes and terminating in a vertically extending baffle wall 7. Thus arranged the gases of combustion pass directly over the superheating tubes 4, as shown, and thus the superheating surfaces abstract from said gases the amount of sensible heat represented by the difference in temperature between the gases when reaching and leaving the superheater B. By my combination of parts I accomplish a result entirely new, in that there is on baffle located between the fuel bed or grate 5 and the superheating surface, hence, such radiant heat from the fuel bed as passes between the rows of water tubes 2 between the superheater and the fire can impinge directly upon the superheating surface, thus greatly increasing their effectiveness. Attention at this point is called to the Reissue Patent No. 12128, to J. P. Sneddon, June 30th, 1903. The construction disclosed in this patent has particular reference to a baffle interposed between the furnace and the superheater 2, and it will be apparent

upon examining this construction that no radiant heat will be permitted to contact with said superheater tube and that if the baffle should be removed to permit the radiant heat to act upon the superheater, then 5 the gases will short circuit in their path of travel and will not flow over the superheating tubes at all. This construction is again evidenced by reference to Letters Patent No. 10 1077117, to John E. Bell, October 28th, 1913, in which the boiler is so constructed that the superheater will receive heat in substantially the same manner as in the above 15 mentioned patent, and if the baffle is removed the gases will also be short circuited.

It is a fact well known to those versed in the art, that if a superheater receives from the boiler steam carrying entrained water, 20 or free water in the form of spray, or "priming" as it is technically called, such water is frequently carried bodily along by the steam, as it comes to the superheater and swept on to the steam mains, instead of being 25 evaporated. The film of steam in contact with the superheating surfaces becomes quickly superheated, and its volume is proportionately increased, so that its velocity is correspondingly increased, while the 30 velocity of wet steam in and about the center of the tube is not so augmented. The effect of this being to concentrate the free water into a thin stream or pencil in the center of the tube where it fails to contact 35 with the superheating surface, and thus passes through the superheater unevaporated. This construction or effect has been clearly set forth in my co-pending application covering a detailed construction of a 40 superheater. Due to the facts concerning superheaters, above set forth, hitherto in general use, it may be stated that it is for this reason that some superheater manufacturers refuse to guarantee the action of 45 their superheaters in case the steam delivered to them from a boiler contains over one per cent of moisture. The present invention provides means whereby this trouble is entirely overcome, in a manner to be 50 presently described.

Referring to Figure 2 of the drawing, the boiler therein illustrated is identical with the form disclosed in Figure 1 with the exception of adding a steam outlet drum and 55 means being provided between the overhead drum 2^a, of the boiler and the steam outlet drum to superheat the steam, so as to relieve it of moisture, before entering the superheater B. The pipe 11 connects the 60 steam outlet drum with the upper header 3, of the superheater, whereby the steam will flow from the outlet drum to the header 12 and will then circulate through the V-shaped tubes 4 to a lower header 8. An outlet pipe 9 is connected to the lower header 65

8 and is employed to conduct steam from the superheater to any suitable point. By providing the steam conducting pipes between the upper drum 2^a and the steam outlet drum, the superheater B is relieved of all 70 necessity of evaporating any moisture in the steam, as the steam entering the same will contain no moisture, consequently none can be carried over to the steam outlet pipe or main 9. 75

Where a lower degree of superheat may be desired than would normally be expected with a superheater placed as in Figures 1 and 2, I position the superheater B as shown in Figure 3. In this form the dried or superheated steam from the steam drum 11 passes through a pipe 12 to a superheater C', which is disposed on a higher horizontal plane than the superheater B and is of similar construction, with the exception that the 80 superheater C' is reversely positioned with respect to the superheater B. The superheater C may, if desired, be connected to the steam outlet pipe 13 of the boiler D. As shown, the superheater C' is located between 85 the second bank of tubes 14 of the boiler D and the "overcomer" or superheating tubes 15 thereof, said superheater C' may be of any convenient design and the one shown has been employed for purposes of illustration only, as the present invention relates 90 more particularly to the location of superheaters within a boiler and not to the method of constructing the same. 95

Where a very high degree of superheat is 100 needed and it is desirable to obtain this in stages, use is made of the superheater C' as just described in series with the superheater B, this construction being fully illustrated in Figure 3, and as shown the steam is conveyed from the lower header 16 of the superheater C' to the upper header 17 of the superheater B by means of a conducting pipe 18. The lower header 19 of the superheater B is connected with the outlet pipe 13. 110

It is obvious however, that the double arrangement of superheater as disclosed in Figure 3 may be applied with equal facility to the boiler as illustrated in Figure 1 and that the principle of operation thereof will 115 not be affected in any way and will operate with equal efficiency, the only difference being that the steam introduced into the superheater will not be relieved of moisture, as this feature can only be accomplished by 120 the superheating tubes 15.

In Figure 4 there has been illustrated another form of boiler comprising six drums connected by banks of tubes in substantially the manner shown, but it is evident that 125 this boiler is merely composed of two boilers, such as are shown in Figures 2 and 3, placed front to front, each using a water drum and a receiving drum in common, but that the gas passages, location of superheater, and 130

action of these parts are precisely the same as in Figures 2 and 3 with the exception of being duplicated. It will be, therefore, apparent that the scope of the invention will be applicable to the construction as illustrated in Figure 4, when taken in conjunction with the showing set forth in Figures 2 and 3.

Summarizing the results produced by the 10 locations of the superheaters above described, it will be seen that the following novel features have been obtained. Firstly, the elimination of moisture from steam before reaching the superheater proper. Secondly, a superheater positioned above one 15 bank of water tubes and below a second bank, thus arranged for free passage of the gases over the superheating surface. Thirdly, a superheater provided in the space 20 above the said second bank of water tubes and arranged below a bank of "overcomer" tubes. Fourthly, to pre-superheat the steam before it enters the separate superheaters, and in either two or three stages to bring 25 the superheat up to any desired temperature. Fifthly, the elimination of baffles between the lower superheater and the furnace to enable the superheater to absorb radiant heat directly from the fuel bed.

Having described the invention, I 30 claim:—

In a steam generating and superheating system, the combination of a water tube boiler comprising lower and upper water 35 drums, a steam-and-water drum and a re-

ceiving drum, a bank of tubes connecting said lower and upper drums and located above the fuel bed of said boiler, a second bank of tubes connecting said upper water drum with said steam-and-water drum, a 40 third bank of tubes connecting the latter drum with said lower water drum, a plurality of steam conveying-and-superheating tubes connecting said steam-and-water drum to said receiving drum, a superheater located between the said steam conveying-and-superheating tubes and the second bank of water tubes, a second superheater placed above the first bank of water tubes and below the second bank of water tubes, means 45 for connecting said superheaters in series, said superheaters comprising sets of headers respectively located between said steam conveying-and-superheating tubes and said second bank of tubes and between said first and second bank of tubes and connected bent tubes to each set of headers with portions thereof respectively parallel to said steam conveying-and-superheating tubes and said second bank of tubes and to said first and 50 second bank of tubes respectively, whereby steam flows successively through said portions of said tubes for successive superheat thereof, and means for connecting said first superheater to said receiving drum. 55

In testimony whereof I affix my signature in presence of a witness.

JOHN P. BADENHAUSEN.
